UNITED STATES PATENT OFFICE

HERBERT H. WILSON, OF LOS ANGELES, CALIFORNIA.

PUNCHING-BAG PLATFORM.

1,242,626.

Specification of Letters Patent.

Patented Oct. 9, 1917.

Application filed December 18, 1916. Serial No. 137,581.

To all whom it may concern:

Be it known that I, HERBERT H. WILSON, a citizen of the United States, residing at Los Angeles, in the county of Los Angeles 5 and State of California, have invented a new and useful Improvement in Punching-Bag Platforms, of which the following is a specification.

The present invention relates to improvements in punching bag platforms, and the objects thereof are to provide a new and efficient manner and means for suspending a punching bag for use within a room or building without marring or defacing the 15 walls thereof, or without securing attachments or hangers permanently to the walls of the room.

Particularly, the object of the invention is to provide a compact and simple means 20 for suspending a punching bag, such means to be readily attached or placed in position for use, and removed for storage in a box or receptacle when not in use.

Another object of the invention is to provide a device adjustable to various heights 25 and positions for the convenience of the user.

In the accompanying drawings, Figure 1 is a fragmental perspective of a door-way, 30 showing a punch bag and a platform therefor embodying my invention. Fig. 2 is a top plan view of the punching bag platform. Fig. 3 is a plan view of a modified form of platform. Fig. 4 is a side elevation 35 thereof.

Referring to the drawings, the punching bag platform constituting the present invention includes the annular ring 1 supported by wire spokes 2 from the hub 3. 40 Hub 3 is hollow and extends upward, being provided with the clamp 4 whereby the upper brace 5, extending within hub 3, may be clamped in different positions relative to ring 1. Brace 5 is provided with a C-clamp 6 by which it may be detachably secured to the upper part 7 of a door casing. To further support and maintain the stability of the device, I have provided side braces 8, 9, angularly extending from the 45 periphery of the ring 1 and provided with C-clamps 10, 11, respectively, which are adapted to engage with side door-casings 12, 13, respectively. Clamps 6, 10, 11, are provided with pads, preferably of felt, to 50 prevent injury to the woodwork or finish of the door-way. Each individual clamp may

be screwed up tightly in accordance with the variations in the door casing, thereby insuring a rigid device when mounted in position for use. The device may be mounted in an open doorway, the clamps 10, 11, having each a thin jaw adapted to pass between the edge of the door and the door casing. A punching bag 14 is suspended 60 at the bottom of hub 3 in the usual manner. 65

In the modified form shown in Figs. 3, 4, the ring 15 is centrally supported within the door-way and between clamps 16, 17, by braces 18. The hub 19, held concentric with ring 15, by arms 20, is provided with 70 a clamp 21 at the top. An upright brace 22, provided with a clamp 23, is adjustable within the hub 19, being clamped in position by clamp 21. Clamps 16, 17, 23, are provided with felt pads 24, which engage 75 with the door casing when the platform is placed in position for use.

To suspend the device in its operative position, an open door-way is employed. The clamps are secured to the casing, and 80 the device is ready for use. Adjustment by means of the clamp on the hub, may be had, whereby the platform may be raised or lowered to the height preferred by the user.

From the above description and drawings 85 it will be seen that I have produced a punching bag platform that will be very convenient to use, that is strong, light, compact, and that will not rattle when mounted in the operative position. 90

What is claimed is:

1. A punching bag platform, comprising an annular ring to receive the impact of the punching bag, a hub therefor, wire spoke elements supporting the hub concentric with the ring, a clamp on the upper end of the hub, a brace extending within the hub, said brace being held in adjusted position by said clamp, angularly extending braces affixed to the periphery of the annular ring, and clamps mounted on the ends of said braces, said clamps being adapted to engage with the side and top members of a door casing. 95

2. A punching bag platform, comprising an annular ring, a hub therefor, a brace extending from the hub, braces angularly extending from the ring, and clamping means affixed to the braces for detachably securing the platform in its operative position. 105

3. A punching bag platform, comprising an impact ring, a hub therefor, braces ex- 110

tending from the hub and ring, and clamping means carried by the braces for detachably securing the impact ring in its operative position.

5. A punching bag platform, comprising an impact ring, a hollow hub therefor, spoke members centrally supporting the hub, a brace clamped to said hub and extending upward, a C-clamp affixed to said

brace, angularly extending braces affixed to 10 the periphery of said ring, and C-clamps affixed to said angularly extending braces, said last-named C-clamps having one jaw made thin for insertion between the end of the open door and the door casing. 15

In testimony whereof I hereunto affix my signature.

HERBERT H. WILSON.
